(57) **CLAIM**

The ornamental design for a display device, as shown and described.

DESCRIPTION

FIGS. 1-8 represent the display device according to the present design in a folded state, with a part of the screen being exposed in a slid state, in which:

FIG. 1 is a front perspective view thereof;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is a rear perspective view thereof.

FIGS. 9 and 10 illustrate the display device according to the present design in a folded state, in which:

FIG. 9 is a front perspective view thereof; and

FIG. 10 is a rear perspective view thereof.

FIGS. 11 and 12 illustrate the display device according to the present design in an unfolded state, in which:

FIG. 11 is a rear perspective view thereof; and,

FIG. 12 is a front perspective view thereof.

In the drawings, the broken lines illustrate portions of the display device that form no part of the claimed design.
